CLAIM

The ornamental design for a link plate for a chain, as shown and described.

DESCRIPTION

FIG. 1 is a top, right perspective view of a link plate for a chain showing our new design;

FIG. 2 is a front elevational view thereof;

FIG. 3 is a rear elevational view thereof;

FIG. 4 is a bottom view thereof, the top view being a mirror image thereof; and,

FIG. 5 is a right side elevational view thereof, the side opposite being a mirror image of the side shown.
